RAILWAY CAR TRUCK

William A. Geiger, Chicago, Ill., assignor to William P. Sidley, M. F. Back, Albert P. Withall, Edwin C. Austin, and George A. Johnson, all of Chicago, Ill., and Alice T. Miner, Chazy, N. Y., as trustees of The William H. Miner Foundation

Application October 13, 1943, Serial No. 506,084

3 Claims. (Cl. 105—197.1)

This invention relates to an improved railway car truck and particularly to improved spring means therefor.

One of the objects of the invention is to increase the spring capacity of railway car trucks without the necessity of materially changing or enlarging the usual side frame and bolster.

More specifically, my object is to supplement the usual coil spring supports by the provision of leaf spring means positioned lengthwise of the side frame and within the confines of the walls of the frame itself to be acted on directly by the bolster.

A further object is to utilize these supplemental springs as a snubbing or shock absorbing means for dampening or cushioning the action of the springs of the car truck to minimize the vibrations imparted to the car body.

Other objects of the invention will appear from the description in connection with the accompanying drawing.

Referring to this drawing,

Fig. 1 is a vertical central section of the central portion of a railway car truck side frame in a direction lengthwise of the car and showing the associated bolster and spring clusters, and illustrating my improvements in connection therewith, this view being taken substantially on the line 1—1 of Fig. 2;

Fig. 2 is a horizontal transverse section substantially on the line 2—2 of Fig. 1;

Fig. 3 is a sectional view similar to Fig. 1, showing the modification of the invention; and

Fig. 4 is a detail vertical section substantially on the line 4—4 of Fig. 3.

In the drawing, A indicates one of the side frame members of a railway car truck. As will be understood by those skilled in the art, a railway car truck includes two side frame members A, a transverse truck bolster B, a channel-shaped spring plank C, and truck springs D. The opposite ends of the spring plank are supported on the bottom members or seats 10 of the truck side frames A, and the opposite ends of the bolster are positioned in the bolster openings E of the side frame for vertical movement therein.

The usual side frame of a railway car truck is in the form of a casting which in general comprises two side walls 11 spaced apart and joined by top and bottom walls 12 and 13, respectively. Openings 14 are generally provided in the side walls, which communicate with the interior or with the space between the said side walls for access to the interior thereof, and other

purposes not directly concerned with this invention.

In addition, a central bolster opening E is provided in the side frame and is bounded by top and bottom walls 15 and 16, and vertical end walls 17, which are joined to the side walls of the frame. The end of the bolster is positioned between the end walls 17 and is guided thereby for vertical movement in the frame, and the bolster has guide lugs 18 which embrace the side walls of the frame to prevent endwise movement of the bolster. The lower portions of the end walls 17 are offset to widen the opening in the frame so that in assembling, the truck bolster can be inserted endwise into the wider opening and then raised up into position; also, the wider portion of the opening provides space for the bolster supporting springs D and the spring plank C. As is well known in the art, the springs D are generally in the form of coil springs, a plurality of which are arranged in a nest or cluster and positioned between the bolster and the spring plank which is supported on the bottom wall 16 of the bolster opening so as to yieldingly support the bolster in the frame. In the present structure, the cluster at each end of the bolster comprises four springs, the upper and lower ends of which bear against top and bottom spring follower plates 19. The bolster end portions are generally rectangular in section and are formed as hollow castings having vertical side walls and horizontal top and bottom walls. In addition to this, the bolster has a general, central, longitudinal, reinforcing wall 20 extending lengthwise of the bolster and parallel with the side walls.

In accordance with my invention, I provide a supplemental spring element F in the frame to increase the spring capacity of the truck and to provide a snubbing action for the main spring D, to minimize the vibrations imparted to the car. The supplemental spring element F is in the form of resilient steel leaves or plates 21, a number of which are superposed one upon the other to form a bundle, the ends of which are enclosed in cap members 22 which hold the leaves assembled. These leaf springs 21 are disposed in the side frame in a direction lengthwise of the car and are thus contained within the confines of said side frame. The springs extend through openings 23 in the vertical end walls 17 of the frame and their capped ends are positioned in the space between the side walls of the frame. In order to prevent endwise displacement of the spring element F, the rods or bars 24 are provided as abut-

ments for the ends of the spring. These bars extend through the side walls of the frame, as shown more clearly in Fig. 2, and their ends suitably riveted. The spring element F also extends through the end portion of the bolster, suitable openings 25 being provided therefor in the vertical end walls of the bolster. These openings 25 are sufficiently large to allow for the relative movement of the bolster with respect to the spring. In like manner, the spring element F extends through an opening 26 in the central partition or rib 20 of the bolster. The top wall 27 of the bolster is arranged to bear or rest upon the top of the spring element F, and this wall is given a suitable curvature so that the spring element F will be given the proper curvature when flexed downwardly. It will thus be seen that the spring capacity of the truck is increased without any material change in the size or formation of the usual side frame and bolster, and that this additional spring capacity is contained entirely within the confines of the side frame and occupies space which has heretofore been unused. In addition, these supplemental springs act as snubbers to dampen the compression and recoil or rebound of the main springs D, by virtue of the movement of the leaves upon each other when the springs are flexed, thus developing a frictional resistance to the main springs. Flexing of the springs in both directions of movement of the bolster is due to the fact that the spring element F is confined between the bottom of the opening 26 in the central partition 20 and the curved top wall of the bolster.

In assembling the structure, the bolster is raised in the side frame until the openings 23 and 25 are in substantial alignment. The springs are then inserted through the openings 14 of the frame and extend through these openings 23 and 25. After being inserted in place in this manner, the caps 22 are assembled on the ends of the spring group and the bars 24 are then put in place.

In the modification shown in Figs. 3 and 4, the spring capacity of the truck is still further increased by the provision of a second set of leaf plate springs G which are positioned in the frame between the side walls thereof and below the main springs D. This group of leaves forming the spring element G is similar to the spring element F, except that they are normally given a curvature so that their ends will bear upon the bottom wall 13 of the side frame, and the central portion thereof will be positioned close to the bottom wall 16 of the bolster opening. This spring element is inserted in place through the frame openings 14 and is held against endwise movement by the cross-bars 27 which are similar to the bars 24 above described in connection with Fig. 1. In order to transmit the movement of the bolster to the spring element G, so that the spring element G will supplement resistance of the main coil springs to the downward movement of the bolster, an extension member 28 is provided, which is positioned between the bottom of the bolster and the spring element G so that its lower end will bear upon the spring element G. This extension may be of any suitable form for the purpose. In the present structure, this extension is disposed in the center of the cluster of main springs D in the space 29 between the springs; and in order that it may conform to

this space, the extension is preferably made cross-shaped in section.

I claim:

1. In a railway car truck, the combination of a railway car truck side frame comprising side walls spaced apart and joined by end walls forming a bolster opening, a transversely disposed bolster having a hollow rectangular end portion movable vertically in the upper portion of said opening, said end portion having openings in its side walls adjacent said end walls of the frame and having means for guiding said bolster in its movement, a group of coil springs seated in said frame between the bottom of said opening and the bottom wall of said rectangular portion of the bolster, a group of flat plate springs extending horizontally lengthwise of the frame through the openings in the side walls of the bolster and through said end walls into the space between said frame side walls and held against vertical movement by said frame side walls, means in said bolster end portion forming a top wall having a downwardly convex surface bearing upon said plate springs to conform to the flexing of said plate springs upon the downward movement of said bolster, and a central rib in said bolster bearing against the under side of said plate springs to flex said springs upwardly and dampen the recoil of said coil springs.

2. In a railway car truck, the combination of a side frame having a bolster opening, a transversely disposed bolster extending through said opening and guided for vertical movement therein, a spring cluster in said opening and positioned between the bolster and the spring seat in said frame, leaf springs disposed lengthwise within the confines of the frame and extending transversely through said bolster, means in said bolster bearing upon said leaf springs, leaf springs disposed lengthwise within the confines of the frame and disposed below said spring cluster, and a column extending from said bolster to said last mentioned leaf springs for transmitting the downward movement of the bolster to said last mentioned leaf springs.

3. In a railway car truck, the combination of a side frame having a bolster opening, a bolster positioned in the upper portion of said opening and guided for vertical movement therein, a group of main springs positioned in said opening between the under side of the bolster and the bottom of said bolster opening, and upper and lower supplemental spring elements disposed within said frame in a lengthwise direction of the car for yieldingly supporting the bolster, said supplemental spring elements each comprising a group of plate springs, said upper supplemental spring elements having their ends anchored in the walls of the frame and extending through the bolster and said lower supplemental spring elements being positioned below the said main springs and having their ends bearing upon the bottom wall of the frame, an extension bar for the bolster positioned between the under side of the bolster and extending downwardly between the coils of the main springs and bearing upon said lower supplemental spring elements for transmitting the downward movement of the bolster to said lower spring elements, and means in said frame for holding the supplemental spring elements against shifting lengthwise of themselves.

WILLIAM A. GEIGER.
